W. J. Ebersole,
INVENTOR
BY Victor J. Evans
ATTORNEY

UNITED STATES PATENT OFFICE

WILLIAM J. EBERSOLE, OF NEW HAMPTON, MISSOURI

FEED AND GRAIN DISTRIBUTOR

Application filed September 4, 1929. Serial No. 390,338.

This invention relates to a distributor box for mills, elevators and the like, for distributing feed, grain, etc., from one point to a plurality of other points, the general object of the invention being to provide the box with a plurality of spouts, with valve means in the box for controlling the feed of material through the various spouts.

Another object of the invention is to so construct and arrange the parts that there is no danger of the material clogging therein and leakage of dust is prevented and the valves can be controlled from the floor of the building in which the device is used.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is a vertical sectional view through the device.

Figure 2 is a section on line 2—2 of Figure 1.

Figure 3 is an elevation.

Figure 4 is an elevation taken at right angles to Figure 3.

In these views, the numeral 1 indicates a casing or box which is constructed in a dust-proof manner and reinforced with strips, as shown at 2. The upper end of the box is connected to a supply pipe 3 through which the material to be distributed flows into the box.

The lower part of the box is divided into four chambers by the partitions 4 and 5, these partitions being arranged at right angles to each other and the partition 4 is of greater height than the partition 5. A gate or valve 6 is fastened to a shaft 7 which passes through the box immediately above the partition 4 and in one position of this valve, the material entering the upper part of the box is directed into the two chambers on one side of the partition 4 and in another position of the valve, the material is directed into the two

chambers on the opposite side of said partition 4. A pair of valves 8 is carried by a shaft 9 which passes through the box immediately above the partition 5, this shaft also passing through the partition 4 and the valves 8 are arranged one on each side of the partition 4. In one position of these valves 8, two of the chambers are closed, while the other two are open, and in the opposite position of the valve, the first two chambers are open and the other two are closed. Thus by manipulating the valves 6 and 8, the material passing into the device can be directed into any one of the four chambers. A depending spout 10 is connected with the lower end of each chamber by a substantially funnel shaped part 10' and a pair of similarly constructed spouts 11 is connected with one side of the device adjacent its lower end and another pair of spouts 12 is connected with the opposite side of the device, each spout being in communication with a chamber. A double gate or valve 13 controls each pair of spouts, and in one position of these double gates, the spouts 11 and 12 will be closed and in another position, the four spouts 10 will be closed and the material will be directed through the spouts 11 and 12.

A double arm 14 is connected with the shaft 7 and a spring 15 connects one end of this arm to a stationary part of the casing and tends to hold the gate or valve 6 in one of its two positions. A cable 16 is connected with the other end of the arm and extends downwardly and is connected to a lever 17 fastened to one of the supports 18 of the device and working over a quadrant 19, this lever being so arranged that it can be reached by a person standing on the floor of the building in which the device is arranged. By lowering this lever, the valve 6 can be swung to its other position. A similar arm 20 is connected with the shaft 9 and a spring 21 connects one end of this arm with a stationary part of the device and a cable 22 connects the other arm with a lever 23 which is similar to the lever 17.

An arm 24 is connected with each of the shafts 25 of the valves 13, and the lower ends of these arms are connected together by a

100

ac

spring 26 which tends to hold the parts with the valves 13 closing the spouts 11 and 12. A cable 27 is connected with the upper ends of the arms 24 and with a lever 28 so that by moving this lever 28 downwardly, the valves 13 will be moved to a position to close the spouts 10 and to open the spouts 11 and 12.

Thus it will be seen that by manipulating the valves 6 and 8, the material entering the distributor box can be caused to flow from the box through any one of the spouts 10 and that by moving the valves 13 to close the spouts 10, the material will be caused to pass through any one of the spouts 11 or 12, according to the position of the valves 6 and 8.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:—

1. A distributor box comprising a casing having its lower part divided into four chambers, a depending spout connected with the lower end of each chamber, a gate for directing the material into one pair of chambers when in one position and to another pair of chambers when in another position, a double gate arranged at rightangles to the first gate and in one position closing one pair of chambers and in an opposite position closing another pair of chambers and manually operated means for manipulating the gates.

2. A distributor box comprising a casing having its lower part divided into four chambers, a depending spout connected with the lower end of each chamber, a gate for directing the material into one pair of chambers when in one position, and to another pair of chambers when in another position, a double gate arranged at rightangles to the first gate and in one position closing one pair of chambers and in an opposite position closing another pair of chambers, manually operated means for manipulating the gates, a spout connected with one side of each chamber and gates for directing the material into said spouts or into the depending spouts.

3. A device of the class described comprising a casing, a pair of partitions in the lower part thereof arranged at rightangles to each other and dividing said lower part into four chambers, a depending spout connected with the lower end of each chamber, one of the partitions being of greater height than the other partition, a shaft passing through the casing immediately above the high partition and paralleling the same, a gate having its lower edge connected with the shaft, said double gate, in conjunction with the first mentioned gate, permitting the material to be directed into any one of the chambers.

of and in another position of the valve, closing the last mentioned space and directing material into the first mentioned space, a shaft passing through the casing immediately above the short partition and paralleling the same, a double gate having its lower edge connected with said shaft, said double gate, in conjunction with the first mentioned gate, permitting the material to be directed into any one of the chambers.

4. A device of the class described comprising a casing, a pair of partitions in the lower part thereof arranged at rightangles to each other and dividing said lower part into four chambers, a depending spout connected with the lower end of each chamber, one of the partitions being of greater height than the other partition, a shaft passing through the casing immediately above the high partition and paralleling the same, a gate having its lower edge connected with the shaft and in one position closing the space on one side of said high partition and directing the material into the space on the opposite side thereof and in another position of the valve, closing the last mentioned space and directing material into the first mentioned space, a shaft passing through the casing immediately above the short partition and paralleling the same, a double gate having its lower edge connected with said shaft, said double gate, in conjunction with the first mentioned gate, permitting the material to be directed into any one of the chambers.

5. A device of the class described comprising a casing, a pair of partitions in the lower part thereof arranged at rightangles to each other and dividing said lower part into four chambers, a depending spout connected with the lower end of each chamber, one of the partitions being of greater height than the other partition, a shaft passing through the casing immediately above the high partition and paralleling the same, a gate having its lower edge connected with the shaft and in one position closing the space on one side of said high partition and directing the material into the space on the opposite side thereof and in another position of the valve, closing the last mentioned space and directing material into the first mentioned space, a shaft passing through the casing immediately above the short partition and paralleling the same, a double gate having its lower edge connected with said shaft, said double gate, in conjunction with the first mentioned gate, permitting the material to be directed into any one of the chambers.

6. A device of the class described comprising a casing, a pair of partitions in the lower part thereof arranged at rightangles to each other and dividing said lower part into four chambers, a depending spout connected with the lower end of each chamber, one of the partitions being of greater height than the other partition, a shaft passing through the casing immediately above the high partition and paralleling the same, a gate having its lower edge connected with the shaft and in one position closing the space on one side of said high partition and directing the material into the space on the opposite side thereof and in another position of the valve, closing the last mentioned space and directing material into the first mentioned space, a shaft passing through the casing immediately above the short partition and paralleling the same, a double gate having its lower edge connected with said shaft, said double gate, in conjunction with the first mentioned gate, permitting the material to be directed into any one of the chambers.

7. A device of the class described comprising a casing, a pair of partitions in the lower part thereof arranged at rightangles to each other and dividing said lower part into four chambers, a depending spout connected with the lower end of each chamber, one of the partitions being of greater height than the other partition, a shaft passing through the casing immediately above the high partition and paralleling the same, a gate having its lower edge connected with the shaft and in one position closing the space on one side of said high partition and directing the material into the space on the opposite side thereof and in another position of the valve, closing the last mentioned space and directing material into the first mentioned space, a shaft passing through the casing immediately above the short partition and paralleling the same, a double gate having its lower edge connected with said shaft, said double gate, in conjunction with the first mentioned gate, permitting the material to be directed into any one of the chambers.

8. A device of the class described comprising a casing, a pair of partitions in the lower part thereof arranged at rightangles to each other and dividing said lower part into four chambers, a depending spout connected with the lower end of each chamber, one of the partitions being of greater height than the other partition, a shaft passing through the casing immediately above the high partition and paralleling the same, a gate having its lower edge connected with the shaft and in one position closing the space on one side of said high partition and directing the material into the space on the opposite side thereof and in another position of the valve, closing the last mentioned space and directing material into the first mentioned space, a shaft passing through the casing immediately above the short partition and paralleling the same, a double gate having its lower edge connected with said shaft, said double gate, in conjunction with the first mentioned gate, permitting the material to be directed into any one of the chambers.

9. A device of the class described comprising a casing, a pair of partitions in the lower part thereof arranged at rightangles to each other and dividing said lower part into four chambers, a depending spout connected with the lower end of each chamber, one of the partitions being of greater height than the other partition, a shaft passing through the casing immediately above the high partition and paralleling the same, a gate having its lower edge connected with the shaft and in one position closing the space on one side of said high partition and directing the material into the space on the opposite side thereof and in another position of the valve, closing the last mentioned space and directing material into the first mentioned space, a shaft passing through the casing immediately above the short partition and paralleling the same, a double gate having its lower edge connected with said shaft, said double gate, in conjunction with the first mentioned gate, permitting the material to be directed into any one of the chambers.

10. A device of the class described comprising a casing, a pair of partitions in the lower part thereof arranged at rightangles to each other and dividing said lower part into four chambers, a depending spout connected with the lower end of each chamber, one of the partitions being of greater height than the other partition, a shaft passing through the casing immediately above the high partition and paralleling the same, a gate having its lower edge connected with the shaft and in one position closing the space on one side of said high partition and directing the material into the space on the opposite side thereof and in another position of the valve, closing the last mentioned space and directing material into the first mentioned space, a shaft passing through the casing immediately above the short partition and paralleling the same, a double gate having its lower edge connected with said shaft, said double gate, in conjunction with the first mentioned gate, permitting the material to be directed into any one of the chambers.

In testimony whereof I affix my signature.

WILLIAM J. EBERSOLE.
